UNITED STATES PATENT OFFICE.

JAKOB SCHMEER, OF WASHINGTON, DISTRICT OF COLUMBIA.

SHOE.

Application filed June 19, 1928. Serial No. 286,562.

This invention relates to shoes, the primary object being to provide a shoe all portions of which except the outer soles, are formed of metal, preferably aluminum.

5 Another object is to provide an all metal shoe having an upper so constructed as to flex under the action of the foot to which the shoe is applied.

A further object is to provide an all metal 10 shoe utilizing a middle sole formed of telescopically connected members extending throughout the length of the sole and held apart yieldingly by an interposed cushioning spring.

15 A still further object is to provide a shoe of this character the outer soles of which can be easily removed and new ones placed in position readily by the user.

It is a well known fact that shoes formed of 20 leather frequently cause ailments of the feet because of the dyes and acids used in the treatment of the leather. Leather shoes are likewise objectionable because they are not water proof, because they are excessively 25 heavy when made sufficiently durable for use by laborers and mechanics, and because many of them frequently become wrinkled and unsightly after being used for a short time.

It is an object of the present invention to 30 provide an all metal shoe which does not have the objectionable features above enumerated and, furthermore, can be easily provided with a coating material of any desired color, will hold its shape indefinitely, can be cleaned 35 readily, and can be made as cheaply as ordinary leather shoes.

It is also an object of the invention to provide a shoe which acts as an efficient support 40 for the foot and ankle, the resilient cushioning middle sole being extended throughout the width of the foot and being equally efficient as a cushioning means throughout its width and length.

With the foregoing and other objects in 45 view which will appear as the description proceeds the invention resides in the combination and arrangement of parts and in the details of construction hereinafter described and claimed it being understood that changes 50 in the precise embodiment of the invention herein disclosed may be made within the scope of what is claimed without departing from the spirit of the invention.

In the accompanying drawings the preferred form of the invention has been shown. 55 In said drawings,

Figure 1 is a side elevation of a shoe embodying the present improvements, the toe and a portion of the heel being shown in section. 60

Figure 2 is a top plan view.

Figure 3 is a bottom plan view.

Figure 4 is an enlarged section on line 4-4, Figure 1.

Figure 5 is an enlarged section on line 5-5, Figure 1.

Figure 6 is a section on line 6-6, Figure 2.

Referring to the figures by characters of reference 1 designates the upper of the shoe formed of sheet aluminum shaped to properly fit the foot of the user and formed preferably in one piece. The insole 2 is made integral with the upper and said upper is open at the front as shown at 3 so that a lace can be used in the ordinary way for holding the shoe closed about the foot. The entire shoe may be lined with any suitable material such as cork, this lining being indicated at 4. For the purpose of rendering the upper freely flexible so as to permit natural flexing of the foot while the shoe is in use, the upper is formed, adjacent to the closed toe portion 5, with a transverse slit 6 extending to points near the bottom of the sides and providing superposed or lapping aprons 7 produced when the shoe is properly shaped following the formation of the slit. This arrangement of lapping aprons is clearly shown in Figure 1. 75

Additional slits 8 are formed transversely within the upper at the sides of the longitudinal slit 3 close to the upper portion of the arch, these slits providing portions which will lap when the upper is properly shaped, thereby to provide aprons 9. Thus it will be seen that when the shoe is applied to a foot, said shoe will be free to flex back of the toe portion and in front of the ankle portion at the top of the arch. 90

The middle sole of the shoe includes an upper plate 10 extending throughout the length of the insole 2 and provided along its edges with a downwardly extended continuous flange 11 the lower edge of which is inturned as shown particularly at 12. This plate may be extended outwardly beyond the sides and toe portion of the shoe in the same manner as the ordinary leather soles project, although it is to be understood that the extent to which this plate projects will depend on the style of shoe that is made. 100

The middle sole also includes a relatively thick bottom plate 13 having a continuous

60

95

105

110

flange 14 which extends upwardly into the space surrounded by the flange 11 and is outwardly as at 15 so as to provide a tight sliding connection between the parts whereby lower plate 13 will telescope relative to the upper plate 10.

Formed in the toe portion of the plate 13 and extending along the sides of said plate back to the front portion of the arch 16 is a groove 17 adapted to receive the reduced edge portion 18 of an outer sole 19 formed of leather or other suitable material. A retaining strip 20 bears against that portion 18 of the outer sole seated in the groove 17 and is held detachably to the plate 13 of the middle sole by screws 21 extending through the strip 20, through the marginal portion 18, and into the plate 13.

It will be understood from the foregoing description that the outer sole 19 will be held securely but detachably to the middle sole and when it becomes worn it can be removed readily simply by removing the screws 21, lifting the holding strip 20 from the shoe, substituting another outer sole 19, and then replacing the strip 20.

Plate 13 is provided, on its back portion, with a depending heel block 22 which can be made integral therewith or fastened thereto by any suitable means. This heel block has a groove 23 extending partly or entirely around the outer edge portion of the bottom thereof and said groove is adapted to receive the reduced marginal portion 24 of a heel lift 25 formed preferably of leather. This marginal portion is held to the heel block 22 by means of a properly shaped holding strip 26 which clamps upon the marginal portion of the heel lift and is held detachably to the heel block by screws 27 or the like. Thus it will be seen that by removing the strip 26 the heel lift can be removed and another substituted therefor without requiring the services of a skilled artisan.

It is to be understood of course that the middle sole made up of the parts 10 and 13 is properly shaped. For the purpose of providing resiliency there is arranged within the middle sole between the members 10 and 13 an undulating spring strip 28 which extends throughout the length of the space between the members 10 and 13 and also extends practically throughout the width thereof. This spring thus provides a yielding support for the foot throughout the width of the shoe and affords a resiliency which is very desirable and equal to or superior to that resulting from the use of all rubber soles.

It is preferred to make of aluminum all parts of this shoe, except the outer sole and the heel lift. Plate 10 can be connected to the insole 2 by any suitable means such as an adhesive, solder, or the like. The entire shoe can be finished with a colored coating of paint or enamel and will maintain a smooth and

attractive finish. The construction of the sole is such as to provide a firm support on which the foot will be well balanced. The shoe is cool during warm weather, is water tight, and provides a comfortable support for the entire foot without interfering with proper flexion. The spring used can be made of a resilient aluminum alloy or, if desired, of any other suitable resilient material. As the shoe is practically all metal but of aluminum, it will be light as well as durable and will be especially adapted for use by mechanics and laborers although the models can be very attractive so as to be worn on any occasion.

Instead of using leather in the formation of the outer sole and the heel lift, these parts can be made of other materials such as rubber, etc.

It is to be understood of course that instead of making the shoe of aluminum any other suitable metals or non-porous materials can be used.

What is claimed is:

1. A shoe including an upper formed in a single piece of metal having an insole integral therewith, said upper being slit longitudinally from the top toward the toe and being slit transversely adjacent the toe and at the upper portion of the instep, said transverse slits providing lapping aprons for sliding contact during flexion of the shoe upper, a middle sole extending throughout the length of the insole and including upper and lower telescopically connected plates providing a space therebetween and cooperating to simulate the middle sole of a leather shoe, a heel extension carried by the lower plate of the middle sole, there being a marginal groove in the bottom portion of the heel extension and a marginal groove in the side and toe portions of the lower plate, an outer sole, a heel lift, separate means for clamping the outer sole and the heel lift to the grooved portions of the plate and heel block respectively, and an undulating spring interposed between the members of the middle sole and extending throughout the length and width of the space therebetween.

2. A shoe including an upper formed in one piece, there being an insole integral with the upper and said upper and insole being made of metal, there being a longitudinal slit in the upper extending from the top thereof to a point adjacent the toe and transverse slits in the upper between the toe portion and the longitudinal slit and at the upper instep portion, said slits providing lapping relatively movable aprons whereby flexion of the upper adjacent the toe portion and the upper part of the instep portion is permitted.

3. A shoe including an upper formed in one piece, there being an insole integral with the upper and said upper and insole being made of metal, there being a longitudinal

slit in the upper extending from the top thereof to a point adjacent the toe, transverse slits in the upper between the toe portion and the longitudinal slit and at the upper instep portion, said slits providing lapping relatively movable aprons whereby flexion of the upper adjacent the toe portion and the upper part of the instep portion is permitted, and a porous lining for the insole and upper.

10 4. A shoe including an upper formed in one piece, there being an insole integral with the upper and said upper and insole being made of metal, there being a longitudinal slit in the upper extending from the top thereof to a point adjacent the toe, transverse slits in the upper between the toe portion and the longitudinal slit and at the upper instep portion, said slits providing lapping relatively movable aprons whereby flexion of the upper adjacent the toe portion and the upper part of the instep portion is permitted, and a metal cushioning middle sole extending throughout the length and width of the shoe.

25 5. A shoe including an upper formed in one piece, there being an insole integral with the upper and said upper and insole being made of metal, there being a longitudinal slit in the upper extending from the top thereof to a point adjacent the toe, transverse slits in the upper between the toe portion and the longitudinal slit and at the upper instep portion, said slits providing lapping relatively movable aprons whereby flexion of the upper adjacent the toe portion and the upper part 30 of the instep portion is permitted, and a metal cushioning middle sole extending throughout

the length and width of the shoe, including superposed telescopically connected members, and an undulating spring interposed between the members and extending throughout the 40 width and length of the middle sole.

6. In a shoe a middle sole including upper and lower members having marginal flanges interfitting, said members being telescopically connected and said flanges cooperating to 45 limit the movement of the members away from each other, and a cushioning spring comprising an undulating strip of resilient metal interposed between the members of the middle sole and extending throughout the 50 width and length of the space therebetween.

7. In a shoe a middle sole including upper and lower members having marginal flanges interfitting, said members being telescopically connected and said flanges cooperating to 55 limit the movement of the members away from each other, a cushioning spring comprising an undulating strip of resilient metal interposed between the members of the middle sole and extending throughout the width and 60 length of the space therebetween, a heel block carried by one end portion of the lower member of the middle sole, there being a marginal groove in the bottom of the heel block and in the toe and side portions of the bottom 65 plate, a heel lift, an outer sole, and holding strips detachably secured within said grooves for binding upon the marginal portions of the heel lift and the outer sole respectively.

In testimony that I claim the foregoing as 70 my own, I have hereto affixed my signature.

JAKOB SCHMEER.
